UNITED STATES PATENT OFFICE.

WILLIAM A. TAYLOR, OF WASHINGTON, DISTRICT OF COLUMBIA, ASSIGNOR
OF ONE-HALF TO GEORGE W. LEESINTZER, OF SAME PLACE.

MAP-EXHIBITOR.

SPECIFICATION forming part of Letters Patent No. 404,805, dated June 4, 1889.

Application filed October 22, 1887. Serial No. 253,096. (No model.)

To all whom it may concern:

Be it known that I, WILLIAM A. TAYLOR, of Washington city, in the District of Columbia, have invented a new and useful Improvement 5 in Map-Exhibitors, of which the following is a specification.

My invention is an improved map-exhibitor; and it consists in certain novel constructions and combinations of parts, as will be herein- 10 after described and claimed.

In the drawings, Figure 1 is a perspective view of my improved exhibitor, parts being broken away. Fig. 2 is a vertical longitudinal section of the exhibitor, and Fig. 3 is a 15 horizontal section on line $x-x$ of Fig. 2.

The framing comprises a base A, sides B B, back C, front piece D, at the top of which is provided a shelf or rest d, and the top E. The front D only extends for about half the 20 height of the device, the space above being open, so the maps may be readily seen when elevated in the manner hereinafter described.

The sides B are provided on their inner sides with vertical guides b for the front slide 25 E' and the maps or charts F. The front slide E' is arranged in the front guides b, and is movable down behind the fixed front D, or up to close the open front of the exhibitor, in order that the device may present a better appear- 30 ance when not in use; also to exclude dust and the like at such time. The slide and the maps, charts, or similar objects F, which are suitably mounted, are connected by cords H with weights I, such cords H extending 35 over pulleys J. These pulleys J are arranged in two series—an inner series j and an outer series j'—the pulleys of said series alternating—that is to say, the pulleys of one series being in a line between the pulleys of the 40 other series, so that weights of the desired size may be employed in wells or boxes K of the smallest cross-sectional dimensions, as will be readily understood from Fig. 1. The guide-grooves for the maps terminate at their 45 lower ends in different horizontal planes, gradually rising from front to rear, so that the maps when all lowered will project at their upper ends above those in front, so that any particular map may be readily picked out 50 of the collection and raised to view, straps or

handles L being usually employed to facilitate the raising thereof. At their upper ends the guides extend to the tops of the sides B, so the maps may be readily inserted or removed by lifting the top E, which is hinged at e at 55 its rear edge, to enable it to be conveniently lifted when so desired.

The sides B are provided with doors M to the weight-wells, so that access may be had thereto for adjusting the weights, or for other 60 desired purposes. Latches or hooks are arranged to secure the doors M. Any desired number of maps may be supported in the exhibitor, limited only by the number of guide-slots and guide-pulleys, which may be in- 65 creased as desired.

The device is convenient in handling the maps, prevents damage to or mutilation of the maps, and forms a neat article of furniture, as 70 shown.

The exhibitor can be made of suitable size to accommodate any size of map, and in practice the edges of the maps are covered with sheet-brass, to stiffen and keep the maps in shape and to prevent their wearing. Where 75 desired, the sliding front piece may have its panels of glass.

It will be understood that, if desired, a single weight working from the back of the exhibitor may be used instead of the side weights 80 shown.

The exhibitor can be made double front and supported so as to be revolved.

Having thus described my invention, what I 85 claim as new is—

1. In a map-exhibitor, the combination of the sides having guides, the weights arranged outside of such guides, cords for connecting the weights with the maps, the short front piece, and the shelf provided thereon, all sub- 90 substantially as and for the purposes specified.

2. The map-exhibitor herein described, comprising the sides, the short front piece terminating below the upper ends of the sides, the shelf d at the upper end of said front 95 piece, the maps movable in guides in said sides, the weights supported in wells in the sides, and the cords connecting the maps and weights, substantially as set forth.

3. In an exhibitor, substantially as de- 100

scribed, the combination, with the framing having guides for the maps, &c., of the guide-pulleys arranged in two series—an inner series and an outer series—the pulleys of one series being arranged in line between those of the other series, substantially as and for the purposes specified.

4. The exhibitor, substantially as herein described and shown, consisting of the base, the sides having guides which terminate at their lower ends in different horizontal planes, and extend at their upper ends to the upper ends of the sides, the front piece and the top hinged, whereby it may be moved from over the guides of the side pieces, substantially as set forth.

5. As an article of office-furniture, a map-chest constructed and arranged to hold a series of maps sliding in vertical grooves and being kept in position for easy inspection in parts by counterbalance-weights alone, the said chest having right and left double sides, forming two accessible lateral receptacles for the hanging and handling of the maps, and provided with a sliding front door or slide, substantially as set forth.

W. A. TAYLOR.

Witnesses:

P. B. TURPIN,
SOLON C. KEMON.

It is hereby certified that the name of the assignee in Letters Patent No. 404,805, granted June 4, 1889, upon the application of William A. Taylor, of Washington, District of Columbia, for an improvement in "Map-Exhibitors" was erroneously written and printed "George W. Leesintzer," whereas said name should have been written and printed *George W. Leesnitzer*; and that the said Letters Patent should be read with this correction therein that the same may conform to the record of the case in the Patent Office.

Signed, countersigned, and sealed this 2d day of July, A. D. 1889.

[SEAL.]

CYRUS BUSSEY,
Assistant Secretary of the Interior.
